ALFRED HEALD, OF PHILADELPHIA, PENNSYLVANIA, ASSIGNOR TO HUGH McCALLUM, ORLANDO CREASE, ANDREW J. SLOAN, AND WM. McCALLUM, OF SAME PLACE.

DESIGN FOR CARPET-PATTERN.

Specification forming part of Design No. 7,137, dated January 27, 1874; application filed January 15, 1874.
[Term of Patent 3½ years.]

Q.

To all whom it may concern:

Be it known that I, ALFRED HEALD, of the city and county of Philadelphia, State of Pennsylvania, have produced or invented a Design for Carpet-Pattern, of which the following is a specification:

The principal features of my design for a carpet-pattern, which are clearly illustrated by the figure of the accompanying drawing, are, the ornamental ground A and the figures B, arranged at equal distances apart on the said ground. The ground A is laid out in small squares, defined by plain light lines, and within each of the said squares is a coil, a, and between the several squares are dots b. Each figure B is of a foliated character, and com-

posed of flowers, leaves, stems, and buds, arranged in a manner so clearly shown in the drawing as to render minute description unnecessary.

Irrespective of the colors employed, I claim—

The within-described design for a carpet-pattern, consisting of an ornamental ground A, and figures B, as represented in and by the accompanying drawing.

In testimony whereof I have signed my name to this specification in the presence of two subscribing witnesses.

ALFRED HEALD.
